United States Patent Office

Des. 234,240
Patented Feb. 4, 1975

234,240

CHAIR

Akihiko Noda and Kunio Onoguchi, Tokyo, Japan,
assignors to France Bed Co., Ltd., Tokyo, Japan

Filed Feb. 28, 1973, Ser. No. 336,482

Term of patent 7 years

Int. Cl. D6—01

U.S. Cl. D6—70

FIG. 1

FIG. 2

FIG. 4

FIG. 5

FIG. 3

FIG. 6

FIG. 1 is a top plan view of a chair showing our design;
FIG. 2 is a front elevational view thereof;
FIG. 3 is a bottom plan view thereof;
FIG. 4 is a right side elevational view thereof;
FIG. 5 is a rear elevational view thereof; and
FIG. 6 is a perspective view thereof.
The left side elevational view is a mirror image of
FIG. 4 and is omitted.

We claim:

The ornamental design for a chair, as shown and
described.
